UNITED STATES PATENT OFFICE.

ANTONINO CONDURSO, OF NEW YORK, N. Y.

LIFE-SAVING DEVICE.

1,264,275.

Specification of Letters Patent. Patented Apr. 30, 1918.

Application filed August 8, 1917. Serial No. 185,171.

To all whom it may concern:

Be it known that I, ANTONINO CONDURSO, a subject of the King of Italy, residing at New York, in the county of New York and State of New York, have invented new and useful Improvements in Life-Saving Devices, of which the following is a specification.

This invention relates to life saving devices, more particularly to devices of the type adapted to be removably secured to the body of the wearer through the medium of an attaching band or belt.

The main object of the invention is the provision of a life-saving device which is adapted to be extended or set up in box-like form, when it is to be used, and to be collapsed in compact form so as to occupy but relatively small space, when not in use, there being also in view in this connection the provision of a life-saving device well adapted to be employed with advantageous results by those who are learning to swim.

With these and other objects in view, the invention resides in the details of construction and in the combination and arrangement of parts herinafter described and shown in the accompanying drawings forming a part of this specification and in which:—

Figure 1 is a view in perspective of the device extended for application to the body of the wearer.

Fig. 2 is a view in perspective of the device in collapsed condition.

Fig. 3 is a view in horizontal section, taken approximately on the line 3—3 of Fig. 4.

Fig. 4 is a vertical longitudinal section, taken approximately on the line 4—4 of Fig. 3.

Fig. 5 is a cross-section, taken approximately on the line 5—5 of Fig. 4.

Like characters of reference indicate like parts throughout the accompanying drawings.

My collapsible life-saving device or belt includes two pairs of complementary frame sections, which are precisely alike, and which are relatively adjustable with respect to each other in an identical manner, one of these pairs representing what

may be referred to as the rectangular bottom portion of the structure, and the other as the rectangular top portion thereof. 55

With more particular reference to the accompanying drawings, the numeral 10 denotes parallel channel-bars, of which the free longitudinal edges of the sides 11 are formed with lateral flanges 12, in order to 60 provide confronting grooves as 13 for the suitable slidable reception of parallel plates as 14, the respective opposite sides of which are provided with longitudinal slots as 15 of such size as to slidably accommodate 65 said lateral flanges as 12. Secured upon the flat faces or sides of the channel bars 10, at the ends thereof by rivets as 16, so as to rigidly connect one with the other, is a cross piece 17. Similarly connecting the 70 plates 14 at their remote ends is a cross piece 18. Another cross piece 19 connects the bars 14 at their forward ends, this bar 19 intermediate its length, being formed with an expanded ear-like portion 20, upon 75 the inner face of which is secured the laterally projecting lugs 21 for the support of a pin or axis 22.

With its inner end engaged upon this axis is an operating lever 23, which lies parallel 80 to the plates 14, and to which is rigidly pinned at 24 a cross arm 25 having rigidly secured in its opposite ends the projecting pins 26, which, passing through eyes as 27 provided for the purpose through the bars 85 14, are adapted to engage in apertures as 28 provided in the channel-bars 10. In this manner, I arrange for the locking or unlocking of the bars 14 with the channel-bars 10, it being obvious that when the operating 90 lever 23 is raised, the pins 26 will be withdrawn from the eyes 28, thereby permitting the bars 14 to be advanced in the channel bars 10 until the cross piece 18 butts against the adjacent ends of the latter, and also that 95 when the bars 14 are extended to bring the eyes 28 in register with the pins 26, the two sections will again be locked by the proper outward movement of the operating lever 23.

The second pair of complementary sections duplicates in all respects, both as to the elements themselves and as to the action thereof, the pair just described, the two pairs being arranged in assembling as bot- 100

tom and top portions of a rectangular box-like figure, as best illustrated in Figs. 1 and 4.

In order to hold and maintain these bottom and top complementary sections apart when the device is to be extended for service, I employ the coil push spring 29, which is positioned between the operating levers as 23 preferably directly in alinement with the intersection of said levers with their respective cross arms 25. The opposite ends of the coil spring are passed through apertures as 30 and bent upon themselves in any suitable manner so as to fixedly secure said spring between the operating levers 23.

Upon the complementary frame sections thus assembled so as to inclose the same to provide a water-tight box-like float, I secure a covering 31 made of rubber or of any suitable water-proof fabric, adapted to prevent the entrance of water into the structure, and yet flexible enough to be folded upon itself when the device is collapsed. This covering 31 is rigidly secured in proper position to the end pieces as 17 and 18 of both the complementary sections; and it is, of course, made of such size that it is held substantially taut all around when the device is extended for use, as best illustrated in Fig. 1. As the box-like structure is collapsed, this covering 31, between the cross pieces as 17 and 18, in longitudinal direction, and between the corresponding cross pieces of each complementary section in the direction of the height of the box, may be folded upon itself, as best illustrated in Fig. 2.

The operating levers 23 are preferably of such length as to extend through the covering 31 at one end for ready manipulation from the outside of the box, the ends 32 being preferably covered water-tight by inclosing pieces as 33 of such size and resiliency as not to interfere with the actuation of said operating levers or with the folding of the covering 31. These operating levers 23 may, however, if desired, be made shorter so that they do not extend beyond the covering 31, but are bent instead toward the adjacent cross pieces as 18, ending in a head 34, so that when the box is to be collapsed, they may be actuated sufficiently from the outside to remove pins 26 from the eyes 28.

As shown in Fig. 1, I prefer to secure to the outside of the covering 31, loops as 35, through which is passed an adjustable strap or band 36, which may be utilized in one instance to attach the device to the body of the wearer, and in another instance to counteract, when the structure is collapsed, the pressure of the spring 29 whereby to maintain it in suitable collapsed condition, as illustrated in Fig. 2.

From the foregoing description taken in

connection with the accompanying drawings, it will readily be seen that this life-saving float or construction is adapted to be collapsed both longitudinally and transversely so that when fully collapsed, it will occupy a space but little greater than one-fourth of its size when extended.

Having thus described my invention what I claim is:—

1. A device of the character described comprising complementary pairs of frame sections, each being similarly extensible lengthwise, independent means for locking each pair in extended position, resilient means engaged between the complementary pairs for holding the same normally apart, and a water-proof covering completely incasing said complementary sections, said covering being engaged upon the sections so as to be taut when said sections are extended and to fold upon itself when said sections are collapsed.

2. A device of the character described, comprising two pairs of complementary frame sections, each pair being similarly extensible in one direction, independent means for locking each pair in extended position, resilient means engaged between the two pairs to hold them normally apart, a water-proof covering completely incasing said sections, said covering being connected to the ends thereof in such manner as to be taut when the sections are extended and to be folded upon itself when said sections are collapsed, and means combined with said covering whereby to attach the device to the body of the wearer, said means also being adapted to secure the sections in collapsed condition when not in use.

3. A device of the character described, comprising two complementary pairs of frame sections, each pair including a rectangular frame with a pair of parallel slideways and a second frame with a pair of parallel bars engaged in said slideways and slide longitudinally therein, locking means combined with said second frames to lock the same in extended position upon said first frames, resilient means engaged between the two pairs of sections to hold them normally apart, a water proof covering completely incasing said frame sections, said covering being engaged upon the ends thereof so as to be stretched taut when the sections are extended, and means for operating against the tension of said spring to hold the sections in collapsed condition.

4. A device of the character described, comprising two complementary pairs of frame sections, each section including a frame having a pair of parallel slideways and a second frame including a pair of parallel bars slideable therein, means combined with each second frame for locking the same rigid with the first frame when in extended

position, an independent hand actuated operating lever for each locking means, a coil spring engaged between the operating levers to hold the complementary pairs normally 5 apart in locked position, a water-proof covering completely incasing liquid-tight said complementary sections, said covering being engaged upon the free ends of said sections in such manner as to be stretched tautly 10 when the sections are extended and to be folded upon itself when the sections are collapsed, and means for holding the sections in collapsed condition.

5. The combination, in a life saving device, of two complementary pairs of frame sections, each pair being similarly extensible in one direction, independent mechanism for locking each pair in extended posi-

tion, means for manually operating the locking mechanism, resilient means arranged between the locking mechanism for each pair to hold the same normally in locked position, said resilient means being also adapted to maintain the complementary sections spaced apart when in locked position, a 20 water-proof covering engaged liquid-tight upon said complementary frame sections, said covering being adapted to be stretched tautly when said sections are extended and to be folded upon itself in two directions 25 when said sections are collapsed, and means for attaching the device when extended, to the body of the wearer.

In testimony whereof I have signed my name to this specification.

ANTONINO CONDURSO.
